ROLLING MILL

Hans L. Schreck, Easton, Pa., and Alexander K. Hamilton, Chicago, Ill., assignors to Treadwell Engineering Company, Easton, Pa., a corporation of Pennsylvania

Application August 14, 1933, Serial No. 684,959½

10 Claims. (Cl. 80—31.1)

The present invention relates to rolling mills and particularly to vertical mills of the type most frequently used in association with horizontal mills in the fabrication of elongated bars.

5 The invention contemplates the provision of a vertical mill, the cooperating rolls of which are located at the upper ends of parallel vertically disposed spindles, the roll supporting, roll adjusting, and driving mechanisms being located below the rolls. The design of the mechanism is such that the mill, without the sacrifice of rigidity and ruggedness, is nevertheless of great compactness, occupying but small floor space and having no portions which project upwardly above the rolls or downwardly below the normal level of the floor 10 or foundation upon which it is mounted. Ready and precise adjustment of the rolls is possible, novel means being included for effecting not only the rapid and accurate simultaneous adjustment of the positions of the rolls but also for the adjustment of the rolls relatively to each other. It is thus easily possible to bring the rolls, respectively, into any desired positions relatively to the rolls of any horizontal mill in connection with 15 which the vertical mill may be utilized, and it is also possible to quickly and easily effect relative adjustment of the rolls to secure proper registration and coaction of the grooves thereof in turning out bars, the finished cross-sectional dimensions of which must be accurate within very small 20 tolerances.

The mill is provided with means for the protection of the spindle supporting bearings, driving mechanism, etc., from the action of water and scale falling from the vicinity of the mill rolls. It likewise includes a novel driving mechanism having individual driving motors for the two rolls respectively, the connection between each motor and the associated roll including a gear fixed upon the roll spindle, the diameter of which 25 gear is greater than the roll diameter, thus giving the motors the greatest possible mechanical advantage in driving. This arrangement is rendered possible by disposing the spindle gears in different horizontal planes, thus allowing them to overlap without interfering with each other. Many other novel features of the invention will 30 be apparent to one skilled in the art.

One embodiment of the invention, which of course may have various forms depending upon local requirements and uses and purposes to 35 which the mill is to be put, is illustrated by way of example in the accompanying drawings, in which:

55 Figure 1 is a side elevation of the mill;

Figure 2 is a top plan view of the same; Figure 3 is a section on line 3—3 of Fig. 2; Figure 4 is a section on line 4—4 of Fig. 3; Figure 5 is a section on line 5—5 of Fig. 3; Figure 6 is a section on line 6—6 of Fig. 3; 5 Figure 7 is a partial section on line 7—7 of Fig. 6;

Figure 8 is a section on line 8—8 of Fig. 3; Figure 9 is a section on line 9—9 of Fig. 3; Figure 10 is a section on line 10—10 of Fig. 2; 10 and

Figure 11 is a section on line 11—11 of Fig. 1. The rolls of the vertical mill are indicated at 10 and 11, these rolls being fixed, respectively, upon the upper ends of the parallel vertical spindles 12 and 13, which spindles are in turn carried by a two-part main frame 14. The main frame is adjustably supported upon a sub-frame 15, and the sub-frame is carried by a base 16 which may conveniently be mounted upon a concrete or other 15 foundation 17.

The base comprises essentially the side rails 18 and 19, the ends of which are bolted or otherwise rigidly secured to the spaced transversely extending members 20 and 21, the side rails being 20 also secured to the concrete base at a plurality of intermediate points, if desired, by means of holding-down bolts such as are indicated at 22. Base rails 18 and 19 comprise slideways or tracks upon which the sub-frame 15 may be horizontally moved or adjusted, this sub-frame having 25 horizontally extending rail engaging wings 23 and 24, with flanges 23' and 24' which project downwardly into positions to engage, respectively, parallel outer surfaces of the heads of the 30 rails 18 and 19 and to thus prevent lateral displacement of the sub-frame on the supporting base. Locking bolts, one of which is indicated at 25 in Figure 11, extend through flanges 23 and 24 respectively at points just inside of the 35 inner faces of the heads of rails 18 and 19, these bolts being provided with enlarged heads 26, which project under the rail heads respectively, and having clamping nuts 27 by means of which the sub-frame can be rigidly clamped, in any 40 desired position of adjustment, to the rails 18 and 19. When it is desired to adjust the sub-frame longitudinally on the base, nuts 27 can, of course, be loosened, these nuts being again 45 tightened after the adjustment has been completed.

For effecting longitudinal sliding movement of the sub-frame upon the base under the close control of the operator, an electric motor 28 is provided, rigidly mounted upon the foundation 50 55

and connected to the sub-frame by mechanism including a short shaft 29 connected to the motor shaft through a flexible coupling 30, a pinion 31 fixed on shaft 29, and a gear 32 meshing with pinion 31 and having an interiorly threaded hub 33 rotatably supported upon the horizontally disposed threaded shaft 34, the inner end of which is rigidly secured to the sub-frame, as shown in Figure 3. Pinion 31 and gear 32 are enclosed within the housing 35 integral with or affixed to the cross member 21 of the base, the hub portion 33 of gear 32 being rotatably supported in spaced bearing members 36 and 37 fixed within this housing, these bearing members likewise comprising limiting stops preventing movement of gear 32 axially of shaft 34. As shaft 34 is non-rotatable, it follows that energization of the motor 28, which is reversible, in either direction, will result in sliding movement of the sub-frame on the rails 18 and 19, provided, of course, that the holding-down bolts 25 previously referred to have been loosened. By this means simultaneous horizontal movement of the rolls is effected, these rolls being supported, of course, by the main frame 14 which is in turn carried by the sub-frame and movable with it.

The square box-like main frame 14 has downwardly projecting from each corner thereof a threaded bolt, these bolts being indicated at 40, the upper ends of the bolts being rigidly attached to the main frame as shown in Figure 6, and the lower or threaded portions passing through parallel apertures in the sub-frame. Mounted upon the sub-frame are four rotatable worm wheels 41, these wheels being interiorly threaded so as to have threaded engagement with bolts 40, respectively, and being exteriorly toothed so as to have engagement with the threads of worm gears 42 fixed upon shafts 43. It will be understood that there are two shafts 43, and upon each such shaft are affixed two worm gears, there being four worm gears in all and four of the worm wheels 41. Mounted upon the projecting ends of shafts 43 (Figure 7) are gears 44, which gears in turn mesh with a pinion 45 fixed on the shaft of a motor 46, which motor is mounted upon a bracket 47 affixed to the end of the sub-frame and movable therewith. It is clear that, by rotation of the rotor of motor 46 in one direction, the four gears 41 will be simultaneously rotated and will therefore equally and simultaneously coact in raising or lowering the main frame by simultaneously lifting or lowering the non-rotatable threaded bolts 40 rigidly secured to the main frame. It thus appears that the operator, by the manipulation of motor 46, which is always under his close control, can raise or lower the main frame of the mill as desired to bring any selected grooved pass of the mill rolls to the desired and necessary elevation. The main frame will remain at the desired elevation by reason of the fact that the raising and lowering gearing just described is of the "non-reversible" type.

For the purpose of relieving the lifting screws 40 of any laterally or horizontally exerted forces which might otherwise be exerted upon them during operation of the mill, I provide two parallel guide posts, indicated at 50 and 51 respectively, the lower ends of these posts being firmly anchored to the sub-frame and the upper portions thereof slidably fitting within correspondingly formed recesses of the main frame, these recesses being preferably lined by bushings 52

and 53 of anti-friction metal. The guide posts 50 project into the apertures in the main frame for all possible vertical adjustments of the main frame upon the sub-frame and hence provide the necessary lateral support at all times.

The box-like main frame itself is formed in two parts, the larger portion 60 having a recess at one end within which the smaller portion 61 is enclosed, these portions being relatively adjustable for the purpose of bringing the rolls 10 and 11 into the desired horizontal and vertical relationship. Spindle 12 of roll 10 is supported in tapered bearings 62 and 63, and spindle 13 of roll 11 is likewise supported in similar bearings 64 and 65. Bearings 62 and 63 are, however, mounted upon the larger part 60 of the main frame while bearings 64 and 65 are mounted upon the smaller part 61 thereof. Fixed on spindle 12 just below bearing 62 is a driving gear of beveled type, indicated at 66, the teeth of this gear facing downwardly and meshing with the teeth of a beveled pinion 67 fixed on the end of drive shaft 68 mounted in suitable bearings supported by the frame, the outer end of the drive shaft 68 being connected by means of a flexible coupling 69 with the rotor of a driving motor 70 mounted upon a bracket 71 fixed to and supported by the main frame. It will be noted that the diameter of gear 66 is somewhat greater than the diameter of the roll 10.

The spindle 13 is driven by very similar mechanism, this spindle having fixed thereon a beveled wheel 72, the teeth of which face upwardly and mesh with the teeth of a beveled pinion 73 fixed on the end of a hollow drive shaft 74 mounted in bearings which are carried by the movable section 61 of the main frame. Hollow shaft 74 is exteriorly toothed at 75, and meshing with these teeth are longitudinally curved teeth 76 formed on the end of a shaft 77 which is in turn connected through a flexible coupling 78 with the rotor of a driving motor 79. Motor 79 is in turn supported upon a bracket 80 fixed to the end of the main frame portion 60 and supported thereby. The driving connection between the motor 79 and pinion 73 permits, by reason of the peculiar interengagement of shafts 74 and 77, slight relative adjustment, both in vertical and horizontal directions, of the frame portion 61 relatively to the frame portion 60. Roll 11 may therefore be horizontally and vertically adjusted relatively to the roll 10 without interrupting or straining the driving connection between this roll and its driving motor 79.

The tapered bearings which support the vertical spindles 12 and 13 not only rotatably carry these spindles and hold them against displacement in a horizontal plane but likewise carry the spindles and rolls and hold them against vertical movements, thus eliminating the necessity of using step or thrust bearings. Cap or housing members are indicated at 81 and 82 respectively, these members having their margins secured to housing portions 60 and 61 and enclosing, with these housing portions, the spindles, bearings, and driving gears and protecting these parts from contact with water and scale which fall from the vicinity of the rolls 10 and 11 during rolling operations. As is obvious also, the housings 81 and 82 assist in supporting the bearings respectively and, in order to withstand the strains transmitted thereto by the bearings, are firmly bolted to the associated frame portions, as indicated at 84 (Figure 5). The housings are of generally similar shape except in that the enlarged portions 75

81' and 82' thereof, which enclose and protect the driving gears 66 and 72 respectively, are differently positioned by reason of the location of these gears in different horizontal planes. The distance between the housings is quite sufficient to allow for all possible relative adjustments of the spindles and rolls. Beneath bearings 63 and 65 are cup-like closure plates 85 and 86 respectively, each of these plates being secured in part to the associated housing and in part to the main frame portion to which the associated housing is attached.

As may be seen most clearly from Figures 4, 5, and 6, the main frame portion 61 is adjustably carried by the main frame portion 60, four adjusting screws 90, which extend through interiorly threaded sleeves 91 in inwardly extending flanges 92 of main frame portion 60, having at their upper ends hardened steel blocks 93 which bear against the under surfaces of outwardly extending flanges 61' of frame portion 60. The entire weight of frame portion 61, roll 11, spindle 13, and its associated bearings and driving gearing is transmitted to the main frame portion 60 through the adjusting screws 90. Vertical adjustment of frame portion 61 relative to frame portion 60 is effected by simultaneous rotation of the four adjusting screws just referred to, and, for the convenience of the operator in effecting the vertical adjustments of roll 11 relatively to roll 10, mechanism is provided for effecting such simultaneous movement of the adjusting screws. This mechanism comprises parallel shafts 92' and 93', respectively, rotatably supported in suitable bearings in the main frame portion 60 and each carrying two spaced worms, which worms are indicated by the numeral 94, the teeth of each of these worms being in mesh with the teeth of a worm wheel 95 keyed upon the lower end of the associated adjusting screw 90. Each of shafts 92' and 93' also carries, fixed upon the end thereof which projects beyond the end of frame portion 60, a spirally toothed gear 96, the teeth of which gears mesh respectively with the mating teeth of gears 97 fixed upon cross shaft 98. This cross shaft is rotatably supported in gear housings 99 affixed to the ends of the main frame portion 60. To one end of shaft 98 is keyed a wheel 100 having a plurality of radially extending recesses 101, into any one of which a suitable hand lever may be inserted by means of which the wheel may be rotated with the result that the adjusting screws 90 are likewise rotated, although at much smaller angular velocities, and the necessary vertical adjustment of roll 11 thereby effected through the lifting or lowering of the main frame portion 61.

By the mechanism just described, a very fine and very accurate adjustment of the elevation of the roll 11 may be effected, which is highly desirable in promoting extreme accuracy in rolling certain shapes, such for instance as rounds. In the rolling of rounds, it is highly important that the grooves of one roll be exactly opposed to the grooves of the companion roll in order that the resulting bar shall have an exactly circular cross-section.

Mechanism is likewise provided for effecting longitudinal sliding movement of the main frame portion 61 relative to the main frame portion 60, frame portion 61 sliding longitudinally of the mill upon the hardened steel blocks 93. This mechanism is most clearly shown in Figures 1, 2, and 9 and comprises essentially two horizontally extending parallel bars or tie rods 110, each bar having an eye at one end through which extends

a cross rod 111, the ends of which are in turn received within suitable apertures formed in the upstanding lugs 112 integral with the main frame portion 60. A spacer is indicated at 113. The opposite ends of rods 110 project through parallel apertures formed in the upper part of main frame portion 61, and the outer ends of these rods are respectively received within casings 114, within which casings are housed worm gears 115 respectively, these gears being interiorly threaded so as to have threaded engagement with rods 110. Gears 115 are confined by the casings in which they are housed against movement relative to main frame portion 61 and axially of rods 110 so it follows that, upon rotation of gears 115 simultaneously in one direction, main frame portion 61 will be moved either to the left or to the right (Figure 9), depending upon the direction of rotation of these gears. Lock nuts are indicated at 116, which nuts must, of course, be loosened prior to any adjustment toward the left (Figure 9). At all events the lock nuts 116 are brought into tight engagement with frame portion 61, after an adjustment has been effected, to lock this member against movement.

In order to effect rotatory movement of gears 115 simultaneously and through the same angular distances, an actuating device is provided which comprises essentially a rotatably mounted cross shaft 117 having fixed thereon worms 118, the teeth of which respectively mesh with those of worm wheels 115. Cross shaft 117 carries at its outer end a hand wheel 119 having a series of radial recesses 120 into which a spoke or hand lever may be inserted to provide sufficient leverage for easy rotation of this member. Obviously, upon rotation of shaft 117, gears 115 will be simultaneously moved through equal angular distances and sliding movement of frame part 61 upon the hardened blocks 93 effected. Holding-down bolts, 40 which function to assist in holding the frame portions 60 and 61 tightly clamped together for all possible relative positions of adjustment, are indicated at 121, these bolts having nuts 122 thereon which must be loosened prior to any adjustment of frame portion 61, whether vertical or horizontal, and which are tightened after such adjustment has been effected. In order that these bolts shall not interfere with the sliding movements of frame portion 61, this frame portion is slotted as at 123 (Figure 9), the bolts projecting through these several slots respectively.

Means is also provided for causing members 60 and 61 to be tightly engaged and frictionally locked laterally of the mill, during all periods of mill operation and in fact at all times except when relative adjustment of these parts is being effected. This means includes wedging elements 125, of which there are two (Figures 5, 6, and 9), each of these wedges being adapted to fit between and engage two relatively inclined mutually facing surfaces of the main frame members 60 and 61. Holding-down bolts for the wedges are indicated at 126, each of these bolts having a T-head 126' which engages in a T-slot 65 formed in main frame member 60. By tightening the nuts 127, the wedges may be forced down into the wedge-receiving recess as tightly as may be desired with the result that the main frame part or portion 61 is thrust to the left (Figure 5), 70 the side thereof which lies opposite the wedges being thrust with great force against the adjacent side wall of portion 60 of the main frame. By means of the wedges just described and the holding-down bolts previously referred to, the 75

- main frame portion 61 is firmly and rigidly gripped and secured within main frame portion 60. Naturally the wedges are released, as well as the nuts 122 of the holding-down bolts, if relative adjustment of the rolls is to be effected.
- It will be appreciated that, in the design of mills to serve in different steel plants, the design and arrangement of the several component elements of the invention may be varied to comply with local requirements, without departure from the spirit and scope thereof.
- Having thus described the invention, what is claimed as new and desired to be secured by Letters Patent is:
15. 1. In a vertical mill, in combination, a two-part main frame, one part being supported upon the other and being horizontally and vertically adjustable relatively thereto, two spaced parallel roll spindles rotatably mounted, respectively, on the two main frame parts, rolls fixed upon corresponding ends of said spindles, spaced bearings supporting said spindles respectively, and a driving gear fixed on each spindle intermediate the supporting bearings for said spindle, each driving gear being of greater diameter than the associated roll and said gears being unequally spaced from the rolls so as to overlap without interfering.
  20. 2. In a vertical mill, in combination, a two-part main frame, one part being supported upon the other and being horizontally and vertically adjustable relatively thereto, two spaced parallel roll spindles rotatably mounted, respectively, on the two main frame parts, rolls fixed upon corresponding ends of said spindles, spaced bearings supporting said spindles respectively, a driving gear fixed on each spindle intermediate the supporting bearings for said spindle, each driving gear being of greater diameter than the associated roll and said gears being unequally spaced from the rolls so as to overlap without interfering, and a driving pinion for each of said gears, the axes of rotation of said pinions being in substantial alignment.
  25. 3. A vertical mill having a main frame formed in two parts, one of said parts having a recess within which the other is adjustably housed, means for effecting relative vertical and horizontal adjustments of said parts, and means including a wedging element attached to one of said parts and adapted to bear against the other, for locking said parts rigidly in any desired position of adjustment, said last mentioned means including vertically disposed holding-down bolts to prevent vertically upward movement of one part relatively to the other, and a plurality of vertically adjustable wedges positioned intermediate oppositely facing substantially vertically disposed surfaces of said parts.
  30. 4. In a vertical rolling mill of the class described, in combination, a base, a sub-frame mounted for rectilinear sliding movement upon said base, power means mounted on said base for sliding said sub-frame, a main frame mounted for relative vertical movement and adjustment upon said sub-frame, power means carried by said sub-frame for effecting said vertical movement of the main frame, rolls carried by said main frame, and power means carried by said main frame for driving said rolls.
  35. 5. In a vertical rolling mill of the class described, in combination, a base, a sub-frame mounted for rectilinear sliding movement upon said base, an electric motor mounted on said
  - base for sliding said sub-frame, a main frame mounted for relative vertical movement and adjustment upon said sub-frame, an electric motor carried by said sub-frame for effecting said vertical movement of the main frame, vertically disposed rolls carried by said main frame, and individual electric motors carried by said main frame for driving said rolls.
  40. 6. In a vertical rolling mill of the class described, in combination, a base, a sub-frame mounted for rectilinear sliding movement upon said base, power means mounted on said base for sliding said sub-frame, a main frame mounted for relative vertical movement and adjustment upon said sub-frame, power means carried by said sub-frame for effecting said vertical movement of the main frame, said main frame comprising two parts, one part being supported upon said adjusting means and the other of said parts being vertically and horizontally adjustable with relation to said first named part, vertical cooperating rolls respectively carried by said main frame parts, power means carried by said first named part for driving said rolls, and a flexible driving connection for the roll carried by said second named part.
  45. 7. In a rolling mill, a base, a substantially closed housing disposed vertically thereof, and carried on ways thereon, means for adjusting the housing transversely of the base, a shaft journaled in the housing with its upper end projecting therefrom and having a roll thereon, a power transmission extending into the housing from a point laterally thereof and intermediate the ends of said shaft, a motor support projecting laterally of the housing, a motor thereon coupled to said power transmission, and a second housing on said base having a shaft journaled therein, the last-mentioned shaft having a roll thereon cooperating with said first-mentioned roll.
  50. 8. In a rolling mill, a base, a main frame supported on the base for vertical adjustment relatively thereto, parallel vertically disposed roll carrying spindles, means rotatably supporting said spindles in the main frame for relative vertical adjustment, a driving motor for each spindle, each such motor being horizontally spaced from the associated spindle and rigidly supported upon the frame, and a power transmission means operatively connecting each motor to the adjacent spindles at a point intermediate the ends of the spindle, one such power transmission means being flexible, to permit relative vertical adjustment of the spindles.
  55. 9. In a rolling mill, in combination, a base, a main frame supported on the base for vertical adjustment relatively thereto, parallel vertically disposed roll carrying spindles, means rotatably supporting said spindles in the main frame for relative vertical adjustment, said means including two vertically spaced bearings for each spindle, a driving motor for each spindle, each such motor being horizontally spaced from the associated spindle and rigidly supported upon the main frame, and a power transmission device operatively connecting each motor to the associated spindle at a point intermediate the vertically spaced bearings rotatably supporting the same, one such power transmission means being flexible, to permit relative vertical adjustment of the spindles.
  60. 10. In a rolling mill, in combination, a base, a main frame supported on the base for vertical

adjustment relatively thereto, parallel vertically disposed roll carrying spindles, two vertically spaced bearings rotatably supporting each spindle in the main frame, a gear fixed on each spindle intermediate said bearings, a driving motor for each spindle, each such motor being horizontally spaced from the associated spindle and

rigidly supported upon the main frame, and a shaft operatively connecting each motor to the gear fixed upon the associated spindle, said shafts being also rotatably supported, respectively, in the main frame.

HANS L. SCHRECK.

ALEXANDER K. HAMILTON.
